UNITED STATES PATENT OFFICE.

EDWARD R. BRYER, OF PORTLAND, OREGON, ASSIGNOR TO J. C. BAYER FURNACE COMPANY, INC., A CORPORATION OF OREGON.

DOMESTIC SAWDUST BURNER.

Application filed May 3, 1926. Serial No. 106,284.

This invention relates to improvements in domestic burners for house-heating utilizing the waste from sawmills as fuel, such as sawdust, hogged or chopped wood waste.

5 The object of my invention is to provide apparatus for burning wood waste such as sawdust which is adapted to be employed in domestic heating furnaces of the usual type and which is of compact and simple 10 construction and substantially automatic in operation, whereby comminuted fuels may be subjected to combustion with efficient results in the effective production of heat and its economical utilization in the furnace.

15 A further object of my invention is the provision of burner apparatus for the consumption of disintegrated fuel which will be self-feeding in its action to the burning area, together with the provision of controllable means for the supply of air both to generate inflammable gases and to support the combustion thereof in the combustion chamber.

25 Other objects and advantages of my invention, and objects relating to details of construction and arrangement of parts will be readily apparent in the course of the detailed description to follow.

30 The accompanying drawings illustrate, by way of example, the preferred form in which my invention may be embodied, in which:

35 Figure 1 is a view partly in side elevation and partly in longitudinal section of a burner embodying my invention shown installed in operative condition in a heating furnace.

40 Fig. 2 is a view partly in plan and partly in horizontal section taken on line 2-2 of Fig. 1.

Fig. 3 is a perspective view of the casing element of my invention shown detached.

45 Fig. 4 is a detached perspective view upon an enlarged scale of the grate element of my invention.

Fig. 5 is a view in vertical cross-section of the apparatus shown in Fig. 4.

Referring to said views the reference numeral 1 indicates generally the casing of my 50 improved burner which may be formed of cast metal and composed of an inner combustion box of separable sections 2 and 3 which may be connected together, as at 5, in a lapped joint that will hold the parts rigidly together and in alignment. The inner

box section 3 is of rectangular configuration in cross-section formed to be inserted within the ash-pit 6 of a heating furnace 7 of the usual type through the front opening 8, usually closed by an ash-pit door, not shown, 60 which may be removed.

The bottom wall 10 of the box 3 may be supported upon the bottom of the ash-pit and the rear wall 11 given a rounded form to adapt it to the usual curved configuration 65 of the ash-pit walls. The upper wall 12 disposed in a plane parallel to the bottom wall 10 is formed adjacent its inner extremity with a circular opening 13 concentric with the rear wall 11 and about said opening a 70 circular rib 15 is formed integrally upon the upper wall within which a cylindrical collar 16 is mounted in axial alignment with the opening 13 and extending upwardly and concentrically through the grate opening 17 of the furnace.

An annular collar-plate 18 is fitted about the collar 16 to block the opening 17 exteriorly of said collar and which may be cemented in place by fire-resisting material of 80 plastic composition to prevent any passage of air or gases into the furnace flues exteriorly of said collar.

The interior of said box section 3 provides a combustion chamber 20. The burner 85 section 2 is disposed mainly upon the outside of the furnace and comprises a bottom wall 21 substantially in horizontal alignment with the bottom wall 10 of the box section and side walls 22 disposed rectangularly thereto and in alignment with the corresponding walls of the box section.

The upper wall of the burner section 2 extends downwardly from its connection with the box section at an angle of approximately 45° from the horizontal, as at 23, and thence upwardly at a suitable angle, as at 25, forming the rear wall of the feed chute of the device. Said walls 23 and 25 provide a reentrant-angular upper wall construction which provides a restricted throat 26 between the lower apex of said walls and the bottom 21.

The feed chute 27 is further formed with a rear wall 28 and side walls formed by the 105 side walls 22 of the burner section and in the same plane thereof.

A front opening 30 is provided of substantially the same area as the throat 26 by the provision of the horizontal wall 31 to 110

2
which a draft door 32 is hingedly connected and adapted to be opened and closed by means of a chain 33 that may extend upwardly through the floor of the building in 5 which the apparatus is placed and whereby control of the draft may be made in a well-known manner.

A hopper 35 of any suitable material, such as sheet metal, is connected to the outer end of the feed-chute 27 and disposed in 10 such vertical relation thereto that disintegrated fuel, such as sawdust, will feed downwardly therein by gravity without attention.

A series of stepped grates are provided— 15 see Figs. 4 and 5—which are adapted to be entered within the door opening 30 and, as shown, may consist in sections 36, 37, and 38, each of which may include vertically disposed spacing-plates 40 of progressively 20 longer length from the top section to the bottom and to which horizontally disposed grate-shelves 41 are integrally connected.

Said grate-shelves may be cut away at 25 their rear, as at 42, or a portion of their width that extends under the grate-sections superimposed thereon. The outer said spacing-plates of the lower two grate-sections may be formed upon their upper edges with a lug 43 and the upper two sections may be 30 formed with corresponding notches 45 in said spacing-plates to receive said lugs, whereby the grate-sections may be maintained in their desired operative position with the grate-shelves 41 in stepped relation. Said assembled grate-shelves may be 35 slidably inserted within the door-opening 30 and supported upon the bottom 21 in more or less advanced position relative to the feed-chute opening 27 and the restricted portion 26, as will be more fully described hereinafter.

A rod 46 is rotatably mounted transversely of the burner-section in the side walls 22 or adjacent to the opening of the feed-chute 45 27 into the burner-chamber. Rocking-arms 47 are pinned to said rod close to the side walls and are adapted to be oscillated in said feed-chute by means of a lever-arm 48 outwardly of the burner-casing to which arm 50 a chain 50 may be connected extending upwardly to a dwelling-room above.

Positioned in the inclined wall 23 of the burner casing a draft opening 51 is formed controlled by a grated shutter 52 to allow 55 more or less air into the combustion chamber for combustion purposes, as will be further explained.

It will be noted that air-spaces 53 and 55 are provided between the top and bottom of 60 the section 3 positioned within the furnace ash-pit and also at the rear of the ash-pit, as at 56. Similarly, the side walls 22 of the casing are spaced from the side walls of the ash-pit to provide sufficient circulation of air 65 through the opening 8 and about the section

3 to prevent the walls of the casing from being overheated to an extent that will cause them to be burned or injured.

The operation of my invention may be explained as follows:

With the parts assembled in the manner described and mounted in the furnace substantially as illustrated, the hopper 35 being full of sawdust or other like fuel and the hopper covered by the closed cover 53, the 75 sawdust will settle down over the grate shelves 41 and somewhat upon the floor 21 within the restricted opening 26.

A fire may be kindled under the grate sections and the draft through the door opening 30 will ignite the disintegrated fuel which, due to its position upon the grate shelves, will provide openings for the passage of air and an effective draft. The flames and heat gases thus produced will be 85 drawn into the combustion chamber 20 and upwardly through the opening 13 into the flues of the furnace 7 and escape to the atmosphere.

As the fire in the sawdust becomes established the draft door 32 may be opened or closed as conditions may warrant, and as the fuel burns away fresh sawdust will slide 90 downwardly through the feed chute 27 and maintain the fire automatically as long as a 95 supply of fuel is retained in the hopper.

The provision of the stepped grate shelves with the air spaces therebetween positioned immediately below the feed chute whereon the disintegrated fuel rests provides an 100 advantageous structure for the burning of this class of fuel as it is thereby prevented from packing in solid masses and air openings are 105 invariably maintained therein automatically so that air to support and maintain combustion will at all times be permitted to pass through the fuel.

The assembled grate shelves may be placed more or less under the feed chute to correspondingly break up the mass of fuel under 110 combustion and whereby the amount of fuel consumed may be regulated.

The gases from the burning fuel will pass through the restricted opening 26 and thence expand somewhat in the combustion chamber 20 where they may be further combined with air admitted through the draft opening 51 to obtain full combustion of the gases.

In order that relatively wet sawdust or the like, which will be prone to pack and clog the feed chute, may be dislocated in the most convenient manner the provision of the rocking arms 47 are provided which may be manipulated from the floor above to oscillate along the sides of the feed chute and break up any stricture of the fuel feed at this point.

From the foregoing description taken in connection with the accompanying drawings the advantages of the construction and ap- 130

lication of my improved domestic sawdust burner will be readily apparent, but, while I have described the principle of operation of the invention together with the devices which I now consider the best embodiment thereof, it will be understood that the structures shown are merely illustrative, and that such changes may be made therein as will lie within the scope of the following claims.

Having described my invention, what I claim is:

1. In a burner of the class described, a casing adapted to be extended within a furnace and having communication with the flues thereof, the portion of said casing exterior to said furnace having a burner-chamber therein and a fuel-supply opening thereabove, and a plurality of movable grate-shelves positioned in said burner-chamber.
2. In a burner of the class described, a casing having an opening at one end adapted to make connection with the flues of a heating furnace, and a burner-chamber at its other end provided with a draft-door and a fuel-feed opening above said burner-chamber, a hopper mounted upon said feed-opening wherefrom fuel may be supplied by gravity to said opening, the upper wall of said casing having a reentrant angular portion affording a restricted passage forward of said chamber, a damper in said wall, and a plurality of grate-shelves arranged in superposed, stepped relation to support the fuel from said feed-opening having air-spaces therebetween to admit air from said draft-door to the fuel supports upon said shelves.
3. In a burner of the class described, a casing having an opening at one end adapted to make connection with the flues of a heating furnace, and a burner-chamber at its other end provided with a draft-door and a fuel-feed opening above said burner-chamber, a hopper mounted upon said feed-opening wherefrom fuel may be supplied by gravity to said opening, the upper wall of said casing having a reentrant angular portion affording a restricted passage forward of said chamber, a damper in said wall, a plurality of grate-shelves arranged in superposed, stepped relation to support the fuel from said feed-opening having air-spaces therebetween to admit air from said draft-door to the fuel supports upon said shelves, and means in said feed-opening to agitate fuel in said feed-opening.

4. In a burner of the class described, including a burner-section, a fuel hopper mounted upon said burner-section having a feed-chute leading to the burner-chamber within said burner-section, and a plurality of stepped grate-shelves positioned in said burner-chamber to receive the fuel thereon, said grate-shelves being movable as a unit in said burner-chamber to support the fuel thereon.

5. A burner of the class described, consisting in combination with a furnace, of a combustion-box section adapted to be positioned within the ash-pit of the furnace and having a combustion-chamber provided with an opening communicating with the flues of said furnace, a burner-section positioned exteriorly of the furnace including a burner-chamber communicating with said combustion-chamber, a series of stepped grate-shelves disposed within said burner-chamber having draft openings between the shelves, a draft-door in said burner-section admitting air to said burner-chamber between said shelves, and a feed-opening for fuel above said burner-chamber.

6. A burner of the class described, consisting in combination with a furnace, of a combustion-box section adapted to be positioned within the ash-pit of the furnace and having a combustion-chamber provided with an opening communicating with the flues of said furnace, a burner-section positioned exteriorly of the furnace including a burner-chamber communicating with said combustion-chamber by a restricted opening, a series of stepped grate-shelves disposed within said burner-chamber having draft openings between the shelves, a draft-door in said burner-section admitting air to said burner-chamber between said shelves, and a feed-opening for fuel above said burner-chamber.

7. A burner of the class described, consisting in combination with a furnace, of a combustion-box section adapted to be positioned within the ash-pit of the furnace and having a combustion-chamber provided with an opening communicating with the flues of said furnace, a burner-section positioned exteriorly of the furnace including a burner-chamber communicating with said combustion-chamber, a series of stepped grate-shelves disposed within said burner-chamber having draft openings between the shelves, a draft-door in said burner-section admitting air to said burner-chamber between said shelves, and a feed-opening for fuel above said burner-chamber, said grate-shelves being slidable longitudinally of said burner-chamber to lie more or less directly below said feed-opening.

8. A burner of the class described, consisting in combination with a furnace, of a combustion-box section adapted to be positioned within the ash-pit of the furnace and having a combustion-chamber provided with an opening communicating with the flues of said furnace, a burner-section positioned exteriorly of the furnace including a burner-chamber communicating with said combustion-chamber, a series of stepped grate-shelves disposed within said burner-chamber having draft openings between the shelves, a draft-door in said burner-section admitting air to said burner-chamber be-

- between said shelves, a feed-opening for fuel above said burner-chamber, and means to introduce air into said combustion-chamber in advance of said burner-chamber.
5. 9. A burner of the class described, consisting in combination with a furnace, of a combustion-box section adapted to be positioned within the ash-pit of the furnace and having a combustion-chamber provided with an 10 opening communicating with the flues of said furnace, a burner-section positioned exteriorly of the furnace including a burner-chamber communicating with said combustion-chamber, a series of stepped grate-shelves disposed within said burner-chamber having draft openings between the shelves, a draft-door in said burner-section admitting air to said burner-chamber between said shelves, a feed-opening for fuel above 15 said burner-chamber, said grate-shelves being slidable longitudinally of said burner-chamber to lie more or less directly below said feed-opening, and means to introduce air into said combustion-chamber in advance 20 of said burner-chamber.
10. A burner of the class described, consisting in combination with a furnace, of a combustion-box section adapted to be positioned within the ash-pit of the furnace and having a combustion-chamber provided with an 25 opening communicating with the flues of said furnace, a burner-section positioned exteriorly of the furnace including a burner-chamber communicating with said combustion-chamber by a restricted opening, a series of stepped grate-shelves disposed within 30 said burner-chamber having draft openings between the shelves, a draft-door in said burner-section admitting air to said burner-chamber between said shelves, a feed-opening for fuel above 35 said burner-chamber, said grate-shelves being slidable longitudinally of said burner-chamber to lie more or less directly below said feed-opening, and 40 means to introduce air into said combustion-chamber in advance of said burner-chamber.
11. A burner of the class described, consisting in combination with a heating furnace, of a casing adapted to be extended 45 within the ash-pit of the furnace and including a combustion-chamber provided with an opening and connections communicating with the flues of said furnace, said casing having a burner-chamber communicating with said combustion-chamber, a 50 dampered opening to admit air direct into said combustion-chamber, a closed hopper for fuel-supply opening into said burner-chamber whereby fuel may be fed thereinto 55 by gravity, a draft-door closing an opening in the forward end of said casing and leading to said burner-chamber, and a plurality of 60 grate-shelves disposed in superposed stepped relation having interstices therebetween, said 65 grate-shelves being movable in said burner-chamber in adjusted relation to said fuel-supply opening.
12. A burner of the class described, consisting in combination with a heating furnace, of a casing adapted to be extended 70 within the ash-pit of the furnace and including a combustion-chamber provided with an opening and connections communicating with the flues of said furnace, said casing having a burner-chamber communicating 75 with said combustion-chamber, the upper wall of said casing having a reentrant angular configuration to provide a restricted passage between said chamber, a dampered opening in said wall to admit air direct into 80 said combustion-chamber, a closed hopper for fuel-supply opening into said burner-chamber whereby fuel may be fed thereinto by gravity, a draft-door closing an opening in the forward end of said casing and leading to 85 said burner-chamber, and a plurality of grate-shelves disposed in superposed stepped relation having interstices therebetween, said 90 grate-shelves being movable in said burner-chamber in adjusted relation to said fuel-supply opening.
13. A burner of the class described, consisting in combination with a heating furnace, of a casing adapted to be extended 95 within the ash-pit of the furnace and including a combustion-chamber provided with an opening and connections communicating with the flues of said furnace, said casing having a burner-chamber communicating 100 with said combustion-chamber, a dampered opening to admit air direct into said combustion-chamber, a closed hopper for fuel-supply opening into said burner-chamber whereby fuel may be fed thereinto by gravity, means to agitate the fuel in said hopper opening to prevent fuel clogging therein, a draft-door closing an opening in the forward end of said casing and leading to said burner-chamber, and a plurality of 105 grate-shelves disposed in superposed stepped relation having interstices therebetween, said 110 grate-shelves being movable in said burner-chamber in adjusted relation to said fuel-supply opening.
14. A burner of the class described, consisting in combination with a heating furnace, of a casing adapted to be extended 115 within the ash-pit of the furnace and including a combustion-chamber provided with an opening and connections communicating with the flues of said furnace, said casing having a burner-chamber communicating 120 with said combustion-chamber, the upper wall of said casing having a reentrant angular configuration to provide a restricted passage between said chambers, a dampered opening in said wall to admit air direct into said combustion-chamber, a closed hopper for fuel-supply opening into said burner-chamber, whereby fuel may be fed thereinto 125 130

by gravity, means to agitate the fuel in said hopper opening to prevent fuel clogging therein, a draft-door closing an opening in the forward end of said casing and leading to said burner-chamber, and a plurality of grate-shelves disposed in superposed stepped relation having interstices therebetween, said grate-shelves being movable in said burner-chamber in adjusted relation to said fuel-supply opening.

15. A burner of the class described, consisting in combination with a heating furnace, of a casing including a burner-chamber and a combustion-chamber, the portion 15 of said casing including said combustion-chamber being positioned within the ash-pit of said furnace, and having an opening directed in vertical alignment with the grate-opening of the furnace, and a collar seated 20 about said casing opening extending into said grate-opening of the furnace.

16. A burner of the class described, consisting in combination with a heating furnace, of a casing including a burner-chamber and a combustion-chamber, the portion 25 of said casing including said combustion-chamber being positioned within the ash-pit of said furnace, and having an opening directed in vertical alignment with the grate-opening of the furnace, a collar seated about 30 said casing opening extending into said grate-opening of the furnace, and a collar-plate about said collar closing the space between said collar and said grate-opening.

35 17. A burner of the class described, consisting in combination with a heating furnace, of a burner-section and a combustion-

box section, the latter section being extended within the ash-pit of the furnace, an opening in said combustion-box section in 40 vertical alignment with the grate-opening of the furnace, a collar positioned about said opening in the combustion-box section and extending into said grate-opening, and means to close the space between said collar and the 45 walls of said grate-opening to prevent the passage of air from the ash-pit into the flues of the furnace.

18. A burner of the class described, consisting in combination with a heating furnace, of a casing including a burner-section and a combustion-box section, said combustion-box section being positioned within the ash-pit of the furnace, and spaced from the side, bottom, and top walls of the ash-pit to 50 afford a circulation of air about said combustion-box section.

19. The combination with a domestic heating furnace, having an ash-pit and a grate-opening connecting said ash-pit with the 55 flues of the furnace, of a burner-casing adapted to be extended within said ash-pit including a combustion chamber communicating with the furnace flues through said grate-opening, said casing including a burner-section 60 having a draft opening, a fuel-hopper mounted on said burner section to supply fuel within said burner section, and a series of separable grate-shelves arranged in stepped relation in said burner section and 65 movable as a unit between said draft-opening and said fuel-hopper to receive thereon more or less of the fuel fed from said hopper.

EDWARD R. BRYER.
